UNITED STATES PATENT OFFICE.

JOHN WATERFIELD, OF PROVIDENCE, RHODE ISLAND, ASSIGNEE, BY MESNE ASSIGNMENTS, TO SHANNOCK NARROW FABRIC COMPANY, OF PAWTUCKET, RHODE ISLAND, A CORPORATION OF RHODE ISLAND.

KNITTING-MACHINE.

1,306,321.

Specification of Letters Patent. Patented June 10, 1919.

Application filed February 7, 1913, Serial No. 746,828. Renewed December 12, 1918. Serial No. 266,517.

To all whom it may concern:

Be it known that I, JOHN WATERFIELD, a citizen of the United States, residing at Providence, in the county of Providence and State of Rhode Island, have invented certain new and useful Improvements in Knitting-Machines, of which the following is a specification, reference being had thereto to the accompanying drawings.

My invention relates to the class of knitting machines for the manufacture of tapes, braids and other flat fabrics, and consists of the novel construction and combination of the several parts and mechanical elements as hereinafter specified and described and as set forth in the claims.

My said improved knitting machine is characterized by the combination of two straight rows of needles, arranged parallel to each other and capable of a limited vertical movement and also a limited lateral movement, which movements are imparted by the needle-supporting means; oscillating mechanism for alternately carrying the threads from the front row of needles diagonally to the rear row of needles and vice versa to knit the same into a suitable pattern or style; thread-feed rollers; needle-latch controlling devices useful in the formation of the loops or stitches; together with mechanism for tightening all the loops or stitches of each transverse row *seriatim* immediately after the formation thereof.

My said machine can make a plurality of tapes, braids, or other fabrics, at the same time, instead of only one at a time, as in previous machines of this class.

In the accompanying drawings like reference numerals indicate like parts in all the figures thereof.

Figure 1 is a front elevation of my improved knitting machine, which is shown as making ten strips of tape at the same time.

Fig. 2 shows the right-hand side of the machine in elevation.

Fig. 3 is a top plan view, on line *u u w w* of Fig. 1, showing the stitch-tightening device, the front cam-shaft with a cam thereon to operate the said device, and also means for rotating the take-up rolls.

Fig. 4 is a view, on an enlarged scale, as seen in part on line *v v* of Fig. 3, of the two

take-up rolls and means for rotating the same, and also of the stitch-tightening devices of my said invention.

Fig. 5 is a top plan view, on line *u u* of Fig. 1, showing the front cam-shaft and means of rotating the same, the belt-shipping apparatus pertaining to said stop-motion, the rear cam-shaft and means of rotating the same, the cams on the rear cam-shaft for giving reciprocating movement to the needle-bars, and also means intermediate the front cam-shaft and stitch-tightening device for operating the latter from the former.

Fig. 6 is a top plan view, as seen on line *t t* of Fig. 1, of the take-up rolls and the worm and gear for operating them.

Fig. 7 is a view, in side elevation, on an enlarged scale of the front cam-shaft and its cam for the vertical reciprocating movement of the needle-lifting bar, and of the rear cam-shaft and its cam for the vertical movement which operates the thread-carriers.

Fig. 8 is a view, partly in top plan and partly in section on line *s s* of Fig. 9, showing the two parallel needle-plates and the intermediate tape-space, and the needles in position, and the covering strips for the needle-hubs.

Fig. 9 is a view, in front elevation of the needle-bar and front needle-lifting bar, and the needles in position thereon, and the push-rods for reciprocating said bars, respectively, and includes other details of the construction, as hereinafter described. This figure is drawn partly in elevation and partly in section on line *r r* of Fig. 16.

Fig. 10 is a plan view of the needle-bar and the feed-space therein for the passage of the tape to the reel or take-up roll and exhibits the knocking-over bits for clearing the loops or stitches from the needles.

Fig. 11 is a view of the same as seen on section line *q q* of Fig. 10.

Fig. 12 is a plan view of the needle-guards to hold the needle-hubs in relative positions.

Fig. 13 is a view of the same as seen on line *p p* of Fig. 12.

Fig. 14 is a side elevation of the covering-strip to confine the needle-hubs in position, upon the needle-lifting bar.

Fig. 15 is a view of the same as seen on line *o o* of Fig. 14.

Fig. 16 is a view in cross section, as seen on line *n--n* of Fig. 9, showing the needle-plates and the tape-space therein, the knock-over bits, needles and needle-hubs, the needle-lifting bars and the cap-plate upon the needle-bars. In this figure the needles (represented by dotted lines) are seen in their highest position.

Fig. 17 is the same as Fig. 16, except that 10 the needles are shown in their lowest position.

Fig. 18 is a view, in side elevation, of one 15 pair of thread carriers in their central position and in relation to the needles, each of which needles by its hook has engaged one of the threads.

Fig. 19 is a similar view, but shows the 20 thread-carriers in their open position. This figure also illustrates the needles in their highest position (with the needle-latches 25 open and prevented from accidental closing), the needle-bars in their elevated position, the stitch-tightening device in its tightening position and the finished tape passing down through the tape-space between the 30 needle-plates to the reel or take-up drum below, which reel, however, is not shown in this figure.

Fig. 20 is similar to Fig. 18, but represents 35 the central position of the thread-carriers in their return movement.

Fig. 21 is similar to that portion of Fig. 19, which exhibits the position of the thread-carriers, and shows how the thread-carriers 35 have changed places, the rear thread-carrier having come to the front and the front thread-carrier having gone to the rear.

Figs. 22 to 39, both inclusive, illustrate 40 the respective positions of the needles and thread-carriers and the consecutive formations of the stitches, and also the periodical positions of the thread-carriers and of the 45 needle-hooks and needle-latches in the progress of the knitting operation.

Fig. 40 is a diagrammatic view to show 50 the relative location of the needles with respect to one another.

Fig. 41 is a diagrammatic view to illustrate 55 the consecutive movements of a thread-carrier in respect to the needles served thereby.

Fig. 42 is a diagrammatic view to illustrate 60 the laying of the loops upon the needles, which results from the thread-carrier movements illustrated in Fig. 41.

Fig. 43 is a diagrammatic view on a 65 greatly enlarged scale, showing the direction and position of the threads and loops interlaced, which constitute the knitted fabric made by this machine.

In the drawings, 1 represents a bench or 70 table provided with standards 2. A shaft 3 is mounted in bearings 4 on the cross-bars 5, extending between standards 2. The shaft 75 6 has two fixed pulleys 6 and 7. A belt 8

operates the pulley 6 and derives motion and power from a main shaft of an engine or other prime motor (not shown).

A fixed shaft 9 is supported on brackets 70 10 with a reel or take-up drum 11 mounted to rotate thereon while being held against longitudinal displacement at one end by a collar 12 fastened to the shaft by a set screw 13. Mounted on the right-hand end of the hub of the reel 11 is a ratchet-wheel 14, and 75 at the side of the wheel is a rocker-arm 15 pivoted to oscillate on the shaft 9. The rocker-arm 15 has a relatively long hub, one end of which abuts the right-hand bearing for the shaft 9 whereby to hold the parts in 80 place on the shaft with the reel 11 bearing against the collar 12. The inner end of the rocker arm 15 is normally held in a depressed position by a coil-spring 16, the upper end of which is fastened to an eye on the lower 85 edge of said arm, while its lower end is secured to an eye on the cross-bar 5.

The outer end of the rocker-arm supports 90 a pawl 17, loosely pivoted thereon, and the free end of this pawl is engageable with the teeth of the ratchet wheel 14. The inner end of the rocker-arm 15 is periodically lifted by the rod 18, which is operated as hereinafter explained.

The bed plate 19 is supported by standards 95 20, 21, provided with flanges 22 and fastened to the bench 1 by bolts 23.

Two cam-shafts 24 and 25, are mounted, 100 respectively, in the standards 20, 21, of the bed-plate 19. At the right-hand end of the cam-shaft 24 two pulleys 26 and 27 are mounted, the pulley 26 being fast on the cam-shaft 24 and the pulley 27 being loose thereon. A belt 28 from the pulley 7 operates the fixed pulley 26 of the cam-shaft 105 24 or the loose pulley 27 of said cam-shaft, as hereinafter explained. A gear 29 is fastened on the cam-shaft 24.

The cam-shaft 25, mounted in the standards 20, 21, derives motion by means of a 110 gear 30, meshing with the gear 29. The gear 30 has twice as many teeth as the gear 29, so that the gear 29 and its cam-shaft 24 complete two revolutions while the gear 30 and its cam-shaft 25 complete one revolution. 115 There are two cams 31 and 32 fastened on the cam-shaft 24, and they give a vertical reciprocating movement to the needle-lifting bars, as hereinafter explained. A shoe or flanged block 33 rides upon the cam 31 120 and a similar shoe or block 34 rides upon the cam 32. A push-rod 35 extends up from the shoe 33 and a push-rod 36 extends up from the shoe 34. These cams are so timed that the push-rods 35 and 36 move simultaneously and equally. The cams 31 and 32 are, respectively, fastened upon the cam-shaft 24 by collars and set screws, as illustrated in Fig. 1.

An arm 37 from the shoe 33, by a pin ex- 125

tending from said arm, engages an eye or loop at the upper end of the rod 18, and said rod is pivotally connected at its lower end with the rocker-arm 15 (see Figs. 1, 2 and 7).

The cam-shaft 24 also carries another cam 38 fixed thereon for operating the stitch-tightening mechanism, as hereinafter described.

10 The rear cam-shaft 25 carries two cams 39 and 40, fastened by collars and set screws, respectively. The cam 39 is shown most plainly in Fig. 7 and bears against a shoe or flanged block 41. A push-rod 42, slightly curved as seen in Fig. 7, extends loosely through an opening in the bed-plate 19 and operates the thread-carriers. This push-rod 42 and the mechanism for operating the thread carriers are shown on the right hand 20 end of the machine in Figs. 2 and 7. It is to be understood, however, that another thread-carrier mechanism (not shown), exactly similar, is upon the left-hand side of the machine operated by the push-rod 43, shown in Fig. 1, extending from the shoe or flanged block 44, which rides upon the cam 40. This cam 40 with its accompanying shoe or flanged block 44 coöperates with the cam 39 and its shoe 41, and gives to its push 30 rod 43 a reciprocating vertical movement precisely like that given to the push-rod 42 and in unison therewith, as hereinafter explained, to actuate the thread-carriers.

The rear cam-shaft 25 also has a cam 45 35 at its left-hand end and fastened thereon. This cam 45 serves to give a horizontal reciprocating movement to the needle-bar, as hereinafter explained. A bracket 46 extends up from the bed-plate 19 and has a 40 bearing in which a rocker-bar 47 is pivotally mounted. This rocker-bar has its lower end forked or bifurcated to extend loosely over the rim of the cam 45, as shown in Fig. 1. Screws 48, 48, in the bifurcation of the 45 rocker-bar 47, lightly contact with the sides of the cam 45 at and near the peripheral rim thereof. The oscillation of the rocker-bar 47, caused by the rotation of the cam 45, gives said movement to the needle bar.

50 A stitch-tightening device is operated by the cam 38 on the front cam-shaft 24 (Fig. 4). The cam 38 gives a reciprocating movement to the shoe or flanged block 49, and this movement is communicated to the rocker-arm 51 by the bent rod 50, fastened to the inner end of said shoe, said rocker-arm being pivotally mounted on the rod 52, and the latter being mounted parallel to the cam-shaft 24 in the standards 20, 21, of the bed-plate 19. The bent rod 50 and the rocker-arm 51 are pivotally connected as shown at 53.

Just below the opening 54 in the bed-plate 19, where the knit fabric passes 65 through, there are two parallel fixed rods 55

and 56 mounted in said standards 20, 21, and a pulling rod 57 is movable back and forth between said rods 55 and 56, said pulling rod 57 being parallel to the rods 55, 56.

This pulling rod 57 has two ends 58, 59, 70 bent at right angles therefrom, and these ends are mounted loosely on the upper end of the rocking-arm 51 by pivots 60, 60.

Two pulleys 61, 62, are loosely mounted on the rod 52. A band 63 is driven by a 75 pulley 64, fastened on the front cam-shaft 24 (Fig. 5), and passes partially around the two pulleys 61, 62 (Fig. 3), and thence around the lower half of the pulley 65 (Fig. 4). The knit fabric, is indicated in Fig. 4 80 by a heavy dotted line, which shows said fabric passing down through the aperture 54 in the bed-plate 19, thence over the front of the rod 55, thence over the rear of the rod 57, thence over the front of the rod 56, 85 thence front of and under a friction take-up roll 66, thence up and over a friction take-up roll 67, and thence to the take-up reel 11 (Figs. 1 and 2), on which reel the finished product of the machine is wound. 90

These two friction take-up rolls 66 and 67 are mounted rotatably beneath the bed-plate 19 in a rectangular frame 68, shown in Figs. 1 and 6. The peripheral surfaces of the two rolls 66 and 67 are roughened, 95 as seen in Fig. 6, to increase their frictional hold upon the tapes or other knit fabrics, which pass between them.

The pulley 65 is fastened on the shaft 69, which is mounted rotatably in bearings 70, 100 71. The shaft 69 has a worm 72, which meshes with a worm gear 73, the latter being fastened upon the right-hand hub of the rear friction take-up roll 67. This roll 67 has on its opposite end a gear 74 (Fig. 6), which 105 meshes with a gear 75 upon the adjacent end of the roll 66. As the gears 74 and 75 are alike, the rolls 66 and 67 revolve in equal times and draw the finished tape or fabric downward, as illustrated in Figs. 1, 2 and 4. 110

The needles and means for giving to them the requisite vertical and horizontal reciprocating movements are described as follows:

The needles are of the kind commonly 115 used in knitting machines and are illustrated in Figs. 16 to 21, both inclusive, and also in Figs. 24, 27, 30, 33, 36 and 39. Each needle has a stem 76, a hook 77 and a pivoted latch 78. On each stem 76 there is a needle 120 hub 79.

The oscillation of the rocker-bar 47 causes a horizontal reciprocating movement of the needle bar 80. This needle-bar 80 is supported in a vertical position in slots in 125 two standards 81, 81^a. The standards 81, 81^a, are mounted on the bed-plate 19 and are secured in place by bolts 82, which pass through flanges 83 into said bed-plate.

The needle-bar 80 has a central longi- 130

tudinal opening or tape-space 84 formed between two parallel needle-plates 85, 85. On each outer surface of the needle-plates 85, 85, is a comb 86, or series of parallel projections with intervening slots, as best represented in Fig. 10. The stems 76 of the needles pass freely into these slots and are supported from lateral displacement by the projections of the comb 86, as illustrated in Figs. 16 to 21, both inclusive.

There are two parallel needle-lifting-bars 87, 87, supported on the two push-rods 35 and 36. The push-rods at their upper ends enter bearings 88 in brackets 89, which project from the front needle-lifting-bar and are held in position by set screws 90. The lifting-bars 87, 87, have projecting plates 87^a at their ends which slide upon the needle-bars 80. The needle-lifting bars 87, 87, are connected by screws and move together (see Figs. 16 and 17).

Thus the needle-bar 80 has a periodical reciprocating horizontal movement, which carries the needle-plates 85 with the needles mounted thereon, and the needle-lifting-bars 87 have also a periodical reciprocating vertical movement, which causes the needles to rise and descend. The extent of this vertical reciprocating movement is illustrated in Figs. 16 and 17, and the extent of the horizontal movement is limited by the throw of the rocker-bar 47, which preferably is to a distance equal to that embracing any two adjacent needles. A cord 91 extends between supports 92, 92, and serves as latch-controlling means, as hereinafter described.

The hubs 79 of the needles rest upon the top of the companion needle-lifting bars 87, respectively, on the front and back of the machine, as seen in Figs. 16 and 17 and on a larger scale in Fig. 19. Against the outer end of the needle-hubs is laid a comb-bar 93, and upon said comb-bar and needle-hubs is laid a covering strip 94, having bent ends and separately shown in Fig. 14. Over the strip 94 and needle-lifting bar 87 and over the edge of the comb 93, is a cap-piece 95, secured by screws 96 to the needle-lifting bar 87, thus confining all said parts and the needle-hubs in proper relation to the needles. A needle-guard 97 prevents the needles from any displacement in their vertical travel.

The threads or yarns are moved from one position to another and properly presented to the needles by means of thread-carriers, whose construction and actuating mechanism are described as follows:

The push-rod 42 operates two sets of thread-carriers, as illustrated in Figs. 1 and 2. The standards 81 and 81^a are shown in Figs. 1, 2 and 7. The bent push-rod 42 extends up loosely through an aperture in a bracket 100 on the standard 81, which bracket serves as a guide and support therefor, and this rod at its upper end enters a

block 101, provided with ear-pieces, in which the said end of the rod 42 is adjustably mounted. Two cross-bars 102, 103, are centrally mounted on a rod 104 for a pivot. Two link-bars 105, 106, are loosely mounted at their lower ends on the block 101 by a pivot 107, and said link-bars 105 and 106 are loosely connected with the lower ends of the cross-bars 102, 103, by pivots 108 and 109, respectively.

At the upper ends of the cross-bars 102, 103, respectively, are pivotally mounted the two rods 110 and 111 (Fig. 2), and upon the rods 110 and 111, the spreader-bars 115 and 116 of two thread-carriers are mounted, respectively, as seen in Figs. 18, 19, 20 and 21. These thread-carriers are centrally mounted on the pivot-rod 104.

The link-bars 105, 106 are also centrally mounted on the pivot-rod 104, and they together with the cross-bars 102, 103, constitute lazy tongs, which open and close alternately as the push-rod 42 rises and descends.

There are two parallel upright posts 112 and 113, which are secured in socket-pieces 165 at the lower ends upon the bed-plate 19, as seen in Figs. 1 and 2.

It is to be understood, as already stated, that the push-rod 43 on the left-hand end of the machine operates a similar set of lazy tongs, but said set is not shown in the drawings.

These two sets of lazy tongs spread and close alternately the series of thread-carriers, but they are not shown in Fig. 1 because they are directly behind the posts 112 and 113, and cannot be seen in a front elevation of the machine, as there represented.

The thread-carriers and their consecutive positions are exhibited in Figs. 18, 19, 20, 21, 24, 27, 30, 33, 36 and 39.

Each thread-carrier 114 (or 114^a) has the obtuse-angled shape illustrated in Figs. 18 to 21, inclusive, and they are arranged in pairs. They are disposed in two sets in parallel rows, one set designated 114 in the drawings, having their upper ends projecting toward the front of the machine and the other set designated as 114^a in the drawings having their upper ends extending toward the rear of the machine. The thread-carriers 114, 114^a, are mounted near their centers upon the pivot rod 104 and oscillate thereon. The front set of thread-carriers 114, whose upper ends project in front, are connected at said ends by a spreader-bar 115, whose function is to spread the threads or yarns. In like manner, the rear set of thread carriers 114^a, whose upper ends project toward the rear, are connected at said ends by another spreader-bar 116, of similar construction as the spreader-bar 115, and serving a like purpose. Each of these spreader-bars 115, 116, has an integral rib 117, or 118, which extends into and fits snugly in slots in the upper ends 130

of said thread-carriers, respectively, and holds them together. The outer longitudinal edge of each spreader-bar is curved or rounded, as shown, to enable the threads to 5 pass smoothly over said edge. Each thread-carrier has in its lower end an eye 119 for the loose passage of a thread therethrough.

In Figs. 18 to 21, inclusive, the threads are shown by a thin dotted line, and the knit 10 fabric is shown by a heavy dotted line. In Figs. 24, 27, 30, 33 and 36, the threads are shown in solid lines.

The thread-carriers 114, 114^a, oscillate between and are supported laterally by slays 15 or reeds 168, as represented in Figs. 18 to 21, inclusive.

At the top of said posts 112, 113, are brackets 169, which extend from collars 170, secured to the posts by set screws 171. A 20 selavage spool or roll 172 is mounted rotatably on a rod 173 which extends between the brackets 169, 169. On the rod 173 is a collar secured thereon by a set screw. The right-hand end of the selavage spool 172 25 abuts said collar, and a spiral spring, bearing against the collar on the left-hand post 112, presses against the left-hand end of the selavage spool 172 and holds the same from longitudinal displacement.

30 Two other brackets 176, 176, extend from collars 177, which are secured by set screws 178 to the posts 112, 113, respectively. A rod 179 is supported at its ends in the brackets 176, 176. The main roll or beam 180 is 35 loosely mounted on the rod 179 and is held from longitudinal displacement by a spiral spring, as shown in Fig. 1.

Two other brackets 181, 181, extend from the collars 182, which are secured to the 40 posts 112, 113, by set screws 183. These brackets support two rods 184, 185, which are parallel with each other, and whose upper and lower ends are bent at right angles, and these bent ends support two sets of 45 combs 186, 186^a, respectively.

These brackets 181, 181, also support a rod 188. A friction roller 187 is loosely mounted on the rod 188. A space is provided at the left-hand end of the roll 187 by flanges, 50 within which space a friction strap 189 passes, whose two ends are secured to spiral springs, fastened at their lower ends to the needle-lifting devices to produce the requisite friction. The strap 189 may have a longitudinal series of holes therein to vary the 55 tension of the springs.

Two other brackets 190, 190, are mounted on collars 191 which are secured to the posts 112, 113, by set screws 192. A spreader 60 bar 193 is supported on a rod 194, mounted in the brackets 190.

On the selavage-roll 172 a plurality of selavage-threads *d* are wound, which, as represented in Fig. 2, pass, some to the front 65 of the spreader-bar 193 (Figs. 2 and 19),

and some to the rear of said spreader-bar, and thence are conducted to the selvage needles, hereinafter named.

The main-roller 180 has a plurality of threads wound thereon, designated by the 70 reference letters *e* *e'*, which pass loosely through the comb-bar 186, thence around the friction-roller 187, thence through the comb-bar 186^a, thence, some of them (marked *e*) through the slots of the 75 spreader-bar 193 on the front thereof, and some of them (marked *e'*) through the slots of the spreader-bar (193) on the back thereof (see Fig. 19). The threads *e*, *e'*, cross each other, as seen in Fig. 19, beneath 80 the rod 194. The threads *e*, *e'*, then cross each other beneath the rod 195, and the thread *e* goes over the rounded edge of the strip 115 of the thread-carrier 114, and the thread *e'* goes over the rounded edge of 85 the strip 116 of the thread-carrier 114^a. The thread *e* then goes through the eye 119 of the thread-carrier 114 to the needles, and the thread *e'* goes through the eye 119 of the thread-carrier 114^a to the needles, all 90 as shown in Fig. 19. In the position of the thread-carriers exhibited in Fig. 21, it is seen that the thread *e* crosses the thread *e'*, and in the same manner, as seen in Figs. 33 and 36 the threads *e* and *e'* so 95 cross each other.

In Fig. 40 is illustrated diagrammatically the relative positions of the needles *a* and *b*. It is seen that by the arrangement there is one single needle at one end of the back 100 row and one needle at the opposite end of the back row. These end needles are denominated the selvage needles. In Fig. 40 the needles of the back row are designated as *M* and the needles of the front row as 105 *N*. The needles *N* are disposed as inter-jacent with the needles *M* of the next row above.

Having thus described the several parts of my improved knitting machine, I will 110 now explain its operation.

The threads from the main roller 180 are each wound once around the friction roller 187. This is provided with a soft covering, such as flannel, wound around it, or 115 with some other suitable material adapted for the purpose, and this increases the friction and draws the threads tightly, which pass from the main roller 180 to the needles. In order to increase this friction to a greater 120 degree, the friction strap 189 is used, shown in Fig. 1. Two spiral springs extend from the two ends of this strap and are fastened, the front one to the bracket 132 (Fig. 1), and the rear one to the rear needle-lifting 125 bar 87, or other suitable support. These spiral springs (one of which is shown in Fig. 1) have each a hook at its 130 end and each hook is engageable with any one of the adjacent holes in the strap 189 to 135

vary the tension of said strap. These springs draw the strap 189 forcibly down upon the spool or channel of the friction roller 187 and retards its rotation, so that it turns only when the downward pull of the needles in the knitting operation actuate said roller to deliver the thread therefrom.

The threads, before reaching the needles, are moved and properly presented thereto by the series of thread-carriers 114, 114^a, which are arranged in pairs, as shown in Figs. 18 to 21, inclusive, one thread carrier for each thread. In the drawings, Fig. 18 represents the first position, Fig. 19 the second, Fig. 20 the third and Fig. 21 the fourth. The travel of one pair of the thread-carriers is diagrammatically represented in plan view in Fig. 41 where *i* indicates a movement of the thread-carrier to the right; *ii* a movement to the front; *iii* a movement to the left; *iv* a movement toward the rear; *v* a movement to the left; *vi* a movement to the rear; and *viii* a movement toward the front. The two inclosed ovals indicate the positions of the needles, around which the thread-carrier make this travel.

In Fig. 42 is a diagrammatic representation of the stitches or loops of thread so laid by the thread-carriers around these needles, the arrows in said figure denoting the course of the thread. In the center these threads have a closed loop made by the knitting mechanism as shown in Fig. 42. This closed loop is formed at the central position where the converging thread-carrier movements *viii*, *i*, approach nearest the converging thread-carrier movements *iv*, *v*.

In Fig. 18 the two thread-carriers 114, 114^a, meet at their lower ends and this is the central point in their oscillatory motion; in Fig. 19 the lower end of the thread-carrier 114 moves to the front and the lower end of the thread-carrier 114^a moves to the rear; in Fig. 20 the thread-carriers 114, 114^a return to their closed or central position the same as in Fig. 18; and in Fig. 21 the lower end of the thread-carrier 114 moves to the rear and the lower end of the thread-carrier 114^a moves to the front.

There are two sets of reeds 168 and each thread-carrier 114, 114^a, oscillates between the opposite companion reeds, as illustrated in Figs. 18, 19, 20 and 21, respectively.

The threads passing smoothly over the rounded edge of the spreader-bars 115, 116 extend to and through the eyes 119 of the lower ends of the thread-carriers 114, 114^a, respectively, to the needles.

The needle-movements will now be described in general terms.

There are two kinds of needle-movements, 65 one is an alternate upward and downward

movement in a vertical plane, and the other is an alternate horizontal movement in said plane.

The vertical reciprocating movement of the needles is accomplished by the following 70 means:

The front cam-shaft 24, in rotating by the power communicated by the fast pulley 26, turns with it the cams 31 and 32, which impart a reciprocating movement to the shoes 75 33, 34. The push-rods 35, 36, which extend up from said shoes 33, 34, are connected at their upper ends (Fig. 9) with the needle-lifting-bars 87. Thus the needles have a regular reciprocating vertical movement by 80 reason of the mounting of the hubs of the needles 76 on the needle-lifting bar 87, held in position by the comb 93, covering strip 94 and cap-piece 95, as represented in Figs. 16 and 24, where it is seen that there are two 85 connected needle-lifting bars 87 and their accessories, one for the front and one for the back of the machine.

The horizontal reciprocation of the needle-bar 80 and of the needle-lifting bars 90 87 therewith is caused by the cam 45 on the left-hand end of the rear cam-shaft 25, as shown in Fig. 5. This cam-shaft gives a movement to the rocker-bar 47, which is pivotally mounted on the bracket 46, and this 95 rocking movement is communicated to the needle-bar 80, back and forth, in each rotation of the cam shaft 25. The length of each horizontal reciprocation is equal to the distance embracing two of the needles 76. The 100 relative positions of the needles to the thread-carriers in the progress of the knitting stitches is shown in Figs. 25 to 28, both inclusive, but will be more fully described in consecutive order in the discussion of 105 Figs. 22 to 39, both inclusive.

As the threads are knitted into the fabric, the said fabric represented in Figs. 1 and 2, and especially in Figs. 18 to 39, inclusive, passes from the needles down between the 110 two needle plates 85, 85, through the tape-space 84, and is subjected to the stitch-tightening mechanism, as shown in Figs. 4 and 19 and presently described, and are wound upon the take-up reel or drum 11. 115

The kind of fabric made by this machine cannot be made sufficiently close and firm on a knitting machine (for the first or best quality of goods) without the use of a suitable stitch-tightening device.

In my said machine, there is provided a stitch-tightening mechanism, which draws each row of stitches as they are formed and are leaving the needles, by taking up the slack of the threads.

By a combination of cam-movements the loops or stitches are closed to any degree required, after leaving the needles, and thus the fabric can be made much tighter than has been hitherto possible in machines of 130

this class. On each rotation of the front cam-shaft 24, the rod 57 is pulled toward the rear of the machine, and the thread which passes, as indicated in Fig. 4, in front of the two fixed rods 55 and 56 is drawn slightly toward the rear by the rod 57, operated by the rocker-arm 51 and the cam 38, as already described. Thus all the stitches are drawn closely together and compacted, 10 and consequently make a firm fabric.

The threads or yarns are fed to the needles by thread-carriers 144, 114^a. The needles descend; and the rod 57 moves forward, (toward the operator), thus releasing the tension on the fabric and causing the stitches to hang loose as the needles begin to form new loops. The friction strap, which is fastened to the bracket 132, as shown in Fig. 1, gets tighter as the needles descend, putting more and more tension on the yarn or threads as the needle bar descends. As the new loops are formed and the old loops are leaving the needles (the tension on the yarn being tight and the old loops loose), the 25 needles draw on the line of least resistance and draw all the slack out of the loops which are leaving the needles, before drawing on the yarn which is under tension on the main roller 180. Then, as the needles move to the bottom and new loops are formed, and the needles begin to rise, the rod 57 moves backward again and puts tension on the fabric.

As the needles rise for the next stitch, the friction strap 189, being connected to the bracket 132, is eased off and allows the needles to rise, thus forming a compact fabric and allowing the thread-carriers 114, 114^a, to perform the necessary movements without excessive strain on the threads or 40 yarns.

It is of great importance that the tension of the yarns or threads which pass from the main roller 180 to the needles should be equalized and made constant. For this purpose, the friction roller 187 is used. This gives a complete control of the tension on the threads or yarns. These, after leaving the main roller 180, are wound once around the friction roller 187. The fact that the 50 main roller 180 is full, or partially full, or nearly empty, makes no difference to this tension. Without this device, the tension would vary greatly and continually. The tension would increase more and more from 55 the time when the main roller 180 was put up full until it was empty, because as the roll of yarn or thread becomes smaller and smaller, the leverage thereof is correspondingly lessened and so the pull or draft upon the thread or yarn is greater and greater. The result would therefore be that the fabric would be made closer, until eventually the threads or yarns would break from too much tension. In my device, this tension is 60 always the same, because the friction roller

187 has only one winding of each thread or yarn thereon, and the diameter is always the same. Thus, the threads or yarns are delivered therefrom to the needles under a constant tension,

As the needles rise, the rod 57 takes up the fabric. If the fabric were not so held, the needles would pull it up. As the needles descend, the rod 57 moves forward and releases the fabric. At that time the friction 75 strap 189 begins to tighten up.

By means of the holes through the strap 189, the spiral springs may be adjustably hooked in said holes to increase or diminish the friction on the roller 187, as may be desired, to vary the tension on the yarns or threads.

In Figs. 22 to 39, inclusive, are shown the several consecutive movements of the thread-carriers and needles, also a view of 85 the stitch-formations. In these representations it is to be understood that Figs. 22, 23 and 24, together, show the first movement; Figs. 25, 26 and 27, the second; Figs. 28, 29 and 30, the third; Figs. 31, 32 and 33 the 90 fourth; Figs. 34, 35 and 36, the fifth; and Figs. 37, 38 and 39 the sixth.

In this series of figures A B and C, represent three thread-carriers and *a* and *b* the two needles of a pair or set, to which said thread-carriers conduct the threads according to the pattern.

In Fig. 22 the needles *a* and *b* are located to the right of the thread-carriers B and C, respectively; in Fig. 25 the needles *a* and *b* 100 are in position to the right of the thread-carriers A and B, respectively; in Fig. 28 the needles *a* and *b* are in position to the left of the thread-carriers A and B, respectively; in Fig. 31 the needles *a* and *b* are in position 105 to the left of the thread-carriers A and B, respectively; in Fig. 34 the needles *a* and *b* are in position to the right of the thread-carriers A and B, respectively; and in Fig. 37 the needles *a* and *b* are in position to the 110 right of the thread-carriers B and C.

In Fig. 22 the needles *a* and *b* are in their highest position; in Fig. 25 they are half-way down; in Fig. 28 they are at their lowest position; in Fig. 31 they are at their highest 115 position; in Fig. 34, they are half-way down and in Fig. 37 they are in their lowest position.

The positions of the needles are the same, respectively, in Figs. 24, 27, 30, 33, 36 and 120 39 as in Figs. 22, 25, 28, 31, 34 and 37 above described, and in Figs. 24, 27, 30, 33, 36 and 39 the positions of the needle-latches are also shown, being open in Figs. 24 and 33 and closed in Figs. 27, 30, 36 and 39.

Comparing Figs. 24, 27, 30, 33, 36 and 39 with Figs. 18, 19, 20 and 21 it will be found that Fig. 24 corresponds to Fig. 19; Fig. 30 with Fig. 18; Fig. 33 with Fig. 21 and Fig. 39 with Fig. 20.

From the positions of the several parts shown in Figs. 22, 23 and 24, the needles *a* and *b* begin to move downward to the position shown in Figs. 25, 26 and 27, and at the same time the thread-carriers change from their wide-open position seen in Fig. 24 to their half-open position seen in Fig. 27, but the needle-hooks have not engaged the threads.

10 In the position of the parts illustrated in Figs. 25, 26 and 27, the needles *a* and *b* have moved to the left and half-way downward and the needle-hooks have engaged the threads and the needle-latches have closed to the hooks. The thread-carriers have also closed half-way.

15 In the position of the parts illustrated in Figs. 28, 29 and 30, the needles have completed their downward movement and then have moved horizontally to the left and are ready for their return movement upward. The needle-hooks are still engaging the threads and the needle-latches are still closed to the needle hooks. The thread-carriers 25 are in their closed position.

20 In the position of the parts illustrated in Figs. 31, 32, and 33, the needles have risen to the highest place again and are ready to begin their horizontal movement to the right. The thread-carriers have come to their open position opposite to that which they had in Fig. 24, as will be seen by the crossing of the threads in Fig. 33, which threads in Fig. 24 are not crossed. The 35 needle hooks are disengaged from the threads and the needle latches are open.

25 In the position of the parts illustrated in Figs. 34, 35 and 36 the needles have moved downward half-way and have made their horizontal movement to the right. The needle-hooks have engaged the threads and the needle-latches have closed the needle-hooks. The thread carriers have closed half-way, the threads still being crossed.

30 In the position of the parts illustrated in Figs. 37, 38 and 39 the needles have completed their downward movement and their horizontal movement to the right, the thread-carriers have closed, the needle-hooks 35 still engage the threads and the needle-latches still are closed to the needle-hooks.

35 The next position will be that shown in Figs. 22, 23 and 24.

40 The stitches and movements as represented in Figs. 23, 26, 29, 32, 35 and 38 are exhibited in top plan view.

45 In the knitting process the needle-latches are closed by the descent of the needle-stem through the thread-loop which has just been laid on the needle by the thread-carriers, and when the loop has been knit into the fabric and the needle has been freed therefrom, the rise of the needle causes the threads from the thread-carriers to engage the needle-

latch and move it downward into its open 65 position as seen in Figs. 24 and 33.

The oscillating movement of the thread-carriers is caused by the cam 39 on the rear cam-shaft 25, which cam operating the cam shoe 41 causes the push-rod 42 alternately to 70 move up and down. In moving up this push-rod opens the lazy tongs (made up of the pivotally connected bars 102, 103, 105, 106), thus opening the spreader-bars 115, 116, to their widest extent, but in moving 75 down the push-rod 42 closes the lazy tongs. As already stated, it is to be remembered that a similar lazy tongs and cam-operated push-rod on the left-hand side of the machine, coöperate with the above-described 80 apparatus on the right-hand side of the machine to oscillate the thread-carriers as specified.

These thread-carriers pass between contiguous reeds of the slay 168 and are confined thereby to one line of oscillation.

The periodical rise and descent of the needles are caused by the cams 31 and 32 of the front cam-shaft 24, which give a vertical reciprocating movement by means of 90 the cam-shoes 33 and 34 on said cams, respectively, and this movement is communicated by the push-rods 35 and 36 to the needle-lifting bars 87, 87. The hubs 79 of the needle-shaft 76 rest upon the needle-lifting 95 bars 87, 87 and are held thereto by the comb-bars 93 and covering strips 94. Thus, the needles rise and fall periodically to the extent illustrated in Figs. 16 and 17, which show them and their associated parts, respectively, in their highest and lowest positions.

The needles derive a periodical reciprocating movement in a horizontal direction by means of the cam 45 on the rear cam-shaft 25, which by pressure within the bifurcation of the bottom of the rocker-arm 47 gives an alternate movement, back and forth, horizontally to the needle-bar 80. This needle-bar has needle-plates 85, wherein the needles are supported vertically by the combs 86, 86. The strip or rod 97 also serves to confine the needle-stems in place, engaging said comb. The cord 91 has its function in preventing the needle-latches 79 110 from flying into an accidental closure to the needle-hooks, when they are not otherwise held in proper and timely relation.

115 It has been stated that the front cam-shaft 24 rotates twice while the rear cam-shaft 25, geared thereto, rotates but once. It is also apparent, as shown by the arrows in Fig. 5, that said cam-shafts revolve in opposite directions. The result is that when the cam 39 is in the position shown in Fig. 120 7 the thread-carriers are in the position shown in Fig. 18 and when the lift 99 of the cam 39 has traveled 180° from the posi-

tion shown in Fig. 7, the thread-carriers are in the position shown in Fig. 21. When the lift 99 of the cam 39 is midway said two positions it is traveling on the concentric 5 portion of said cam, and at that time the thread-carriers "dwell" or remain temporarily still as illustrated in Figs. 18 and 20.

The stitch-tightening mechanism is operated from the front cam-shaft 24 by the 10 cam 38, which imparts a reciprocating movement to the cam-shoe 49. This motion is communicated by the curved rod 50 from the cam-shoe 49 to the rocker-arm 51. The rocker-arm gives reciprocating movement to 15 the pulling-rod 57, which draws the knitted fabric (represented by a dotted line in Figs. 11 and 26) between the fixed rolls 55 and 56.

This stitch-tightening device co-operates with the friction take-up rolls 66, 67. A 20 pulley 64 on the front cam-shaft 24 causes a band (shown in dotted lines in Figs. 3 and 5) to travel from the pulley 64 and the loose or idle pulleys 61, 62, to the pulley 65. The pulley 65, being tight on the shaft 69, 25 rotates said shaft, which turns with it the worm 72, to operate the worm-gear 73. The worm-gear 73, fast on the shaft on which the rear take-up roll 67 is secured, turns the roll 67, which by its gear 74, meshing with 30 the gear 75, causes the front take-up roll 66 to rotate also. The knit fabric is drawn by the rolls 66, 69, and passes to the take-up reel or drum 11.

The stitch-tightener operates after each 35 row of stitches has been formed, and the rearward pull of the rod 57 draws in the slack of the threads, while the parts shown in Fig. 19 are in the position there illustrated, the friction take-up rolls 66, 67, resisting any pull upward therefrom. The cam 38 on the cam-shaft 24 is so timed with 40 relation to the cams 31 and 32 on said cam-shaft 24, and also with the pulley 64 on said shaft 24 and the pulley 65 on the shaft 69, that the stitch is tightened when the needles are at their lowest position and disengaged from the threads, as represented in 45 Fig. 19.

The lift 99 on the cam 39 gives the vertical reciprocating movement to the rod 42 to operate the lazy tongs, and so to cause the opening and closing of the spreader-bars 115, 116, and thread-carriers 114, 114^a. This imparts a downward movement to the 55 rod 42 when the cam is passing to its position shown in Fig. 7 and an upward movement while the lift 99 approaches and comes to a position 180° from that shown in said figure.

60 A variety of other stitches can be made by changing the movements and relations of the needles with respect to the oscillating thread-carriers and thus the pattern of the knit fabric can be changed.

In every rotation of the front cam-shaft 65 24, the cam 33 gives a reciprocating movement to the cam-shoe 33 and so the arm 37 extending from said cam-shoe periodically gives a slight pull on the rod 18, and the rocker-arm 15 is oscillated thereby and 70 causes the pawl 17 to advance the ratchet-wheel 14 and to give a corresponding partial rotation to the reel 11 for the purpose of winding thereon the finished fabric.

The lifts 99 of the cams 39 cause the alternate rise and fall of the rods 42 operating the lazy tongs. Therefore in each rotation of the rear cam-shaft 25, said rods move upwardly once and downwardly once, while by the proportionate gearing (29 and 30) 80 the front cam-shaft 24 rotates twice and alternately raises and lowers the needle-lifting-bar 87, 87, twice, as already explained. All the cams hereinbefore described must be accurately placed and timed 85 in order to accomplish a perfect operation of the machine. In Fig. 40 is shown diagrammatically the arrangement of the needles for the manufacture of the improved knit fabric made upon my knitting machine 90 hereinbefore described. If there are five needles employed, they are arranged in two parallel rows, one of which has three needles and the other of which has two needles, the two end needles are the selvage-needles, 95 so called because they knit the selvage of the fabrics.

In Fig. 41 is shown in straight lines the consecutive linear movements of the thread-carrier in relation to the two needles there 100 represented; and in Fig. 42 is shown the loops or stitches so laid upon these needles by said movements of the thread-carriers and the central location of the knitted knot which ties said loops together midway of 105 the needles.

In Fig. 43 the fabric, which is formed by my knitting machine is shown on a greatly enlarged scale. It is, however, to be understood that this figure is intended to illustrate the shapes and relative positions of the loops, and therefore every thread is distinctly represented in a loose interconnection, while in practice, however, all the threads, as soon as each transverse row has 110 been formed are drawn compactly together by the stitch-tightening mechanism hereinbefore specified to form a firm, close fabric.

The knitting machine as shown and described is adapted to make simultaneously a 120 plurality of flat tapes, braids or similar narrow fabrics, as shown in Fig. 1, where each pair of parallel lines from the bed-plate 19 to the take-up reel or drum indicates a separate tape or braid. This same machine, however, by a substitution of other cams and some other parts than those described can be adapted for the manufacture of tubular 125

lacings and other fabrics which have no selvages. Such substituted parts and the fabrics made by their use are reserved as subject matter for a future application, or 5 for future applications for Letters Patent of the United States.

I claim as a novel and useful invention and desire to secure by Letters Patent:—

1. In a knitting machine, the combination 10 with a plurality of pivotally-mounted thread carriers situated in axial alinement and arranged in pairs, the thread-carriers of each pair being adapted to have a shear-like opening-and-closing movement, of 15 means connecting each thread-carrier of a pair to all of the corresponding thread-carriers of the other pairs, a plurality of knitting needles, a needle bar on which said needles are supported for vertical movement, 20 a thread-roll adapted to deliver thread to all of said thread-carriers, respectively, and thereby to all of said needles, mechanism to impart to all the pairs of thread-carriers positively and simultaneously said 25 opening-and-closing movements thereof, mechanism to impart to said needle bar a horizontal reciprocation, and means to reciprocate said needles vertically.
2. In a knitting machine, the combination 30 with a plurality of pivotally-mounted thread-carriers situated in axial alinement and arranged in pairs and each provided at its lower end with a thread-guiding eye, the thread-carriers of each pair being adapted 35 to have a shear-like opening-and-closing movement, of means connecting each thread-carrier of a pair to all of the corresponding thread-carriers of the other pairs, a plurality of knitting needles situated beneath the 40 thread-carriers, a thread-roll carrying threads and delivering them to the thread-carriers, respectively, through the eyes thereof, a needle bar on which the needles are supported for vertical movement, means to 45 reciprocate the needles vertically, means to impart to said needle bar a horizontal reciprocation, and mechanism to impart simultaneously and positively to all the thread-carriers said shear-like movements of oscillation 50 in timed relation with the movements of the needles.
3. In a knitting machine, the combination with a plurality of thread-carriers situated in axial alinement and arranged in pairs 55 side by side, each thread-carrier being pivotally mounted intermediate of its ends and having a thread-guiding eye at its lower end, the thread-carriers of each pair being adapted to have a shear-like movement, of means 60 connecting together the upper ends of all the thread-carriers which project toward the front of the machine, means connecting together the upper end of all the thread-carriers which project toward the rear, a plurality of knitting needles situated beneath 65 the thread-carriers, a thread-roll carrying threads and delivering them to the eyes of the thread-carriers, a needle bar on which said needles are supported for vertical movement, means to reciprocate the needle bar 70 horizontally, means to move the needles vertically, and means to impart simultaneously to all the thread-carriers said shear-like movements of oscillation.
4. In a knitting machine, the combination 75 of a main shaft; a pair of two obtuse-angled plates of metal placed side by side so that when their lower ends overlie one another the upper ends flare outwardly; a pivot on which said plates are loosely mounted; an 80 eye in each plate at the bottom thereof; a needle for each member of said pair provided with a hook at its upper end and with a pivotally-mounted latch beneath said hook; a thread-supply delivering a thread to 85 each of said members through the eye thereof to a position where said hook is engageable therewith; mechanism operated by the shaft and adapted to lift the needles into proximity with the pair of thread-carriers 90 and between them when their lower ends are in an open position angularly; means operated by the shaft and adapted to lower said needles into engagement with the threads; means operated by the shaft and adapted to 95 move the needles periodically in a horizontal plane at right angles with said needle-lifting movement alternately right and left; and means operated by the shaft and adapted alternately and periodically to open and 100 close the lower ends of said thread-carriers.
5. In a knitting machine, the combination of a main shaft; a plurality of pairs of thread-carriers, each of which pairs comprise two obtuse-angled plates of metal 105 placed side by side so that when their lower ends coincide in position the upper ends flare outwardly; a pivot on which said plates are loosely mounted; a bar having its outer edge rounded and provided with a rib, 110 which is secured in slots therefor in the upper ends of these thread-carrier plates which project to the front, and a similar bar secured in slots therefor in the upper ends of those thread-carrier plates which project to 115 the rear; an eye in each plate at the bottom thereof; a needle for each member of each pair of thread-carriers, provided with a hook at its upper end and with a pivotally-mounted latch beneath said hook; a 120 thread-supply delivering a thread to each of said members through an eye thereof to a position where said hook is engageable therewith; mechanism operated by the shaft and adapted to lift the needles into proximity with the pair of thread-carriers and between them when their lower ends are in an open position angularly; means operated by the shaft and adapted to lower the needles into engagement with the threads; 125 130

means operated by the shaft and adapted to move the needles periodically in a horizontal plane at right angles with said needle-lifting movement alternately right and left and so 5 to change the position of the needles horizontally in their relation to the thread-carriers; and means operated by the shaft and adapted alternately and periodically to open and close the lower ends of said thread-carriers.

6. In a knitting machine, the combination of a main shaft; a set of knitting needles, each having a needle-hub; a needle-bar, on which said needles are mounted; means for 15 imparting from the main shaft a horizontal reciprocation to the needle-bar; a needle-lifting bar, on which the needle hubs are secured in position; means for imparting from the main shaft a vertical reciprocation to 20 the needle-lifting bar upon the needle bar; a thread-supply; thread-carriers pivotally mounted on a support above said needles adapted to conduct threads from the thread-supply to said needles; means from the main 25 shaft for imparting a vibratory movement to the thread-carriers; and stitch-tightening mechanism operated from the main shaft and imparting movement to the stitch-tightening devices for the purpose of drawing 30 tight the threads immediately after the formation of the stitches.

7. In a knitting machine, the combination of a main shaft; a cam-shaft rotatably mounted in bearings and rotated by means 35 actuated by the main shaft; a cam on the cam-shaft; a shoe on the cam; a push-rod extending from the cam-shoe; a pivotally mounted rocker-arm, pivotally connected at its lower end with the push-rod; a pulling 40 rod, having bent ends which are mounted on a pivot rod, which rod at its right-hand end is loosely connected with the upper end of the rocker-arm; two fixed rods mounted beneath the bed-plate of the machine and between 45 which two fixed rods said pulling rod is movable; take-up rollers adapted to hold the knitted fabric by their friction therewith; a spring to give return movement to the rocker-arm after its said machine actuation; a knitting mechanism comprising needles; devices to carry thread from a thread-supply to said knitting-mechanism; means 50 to operate the knitting mechanism; and thread-feed, and a stitch-tightening device located between the knitting mechanism and said take-up rollers, the knitted fabric passing in front of the fixed rollers and on the rear of the pulling rod and between the friction take-up rollers.

8. In a knitting machine, the combination of a main shaft; a front cam-shaft; a cam on the cam-shaft; two fixed rods mounted in standards of the machine; a pulling rod movable between the two fixed rods; means 55 operated by said cam to draw the pulling

rod inwardly between the two fixed rods; knitting mechanism operable by the main shaft; a thread-feed operable from the main shaft and adapted to conduct threads to the knitting mechanism; and a take-up roll on 70 which the finished fabric is wound, which pulling rod when moved into alignment with said two fixed rods is capable of taking up the slack of the thread and tightening the stitches immediately after they are knit.

9. In a knitting machine, the combination of knitting mechanism; a main shaft adapted to operate said mechanism; a plurality of needles; a thread-supply for said needles; a stitch-tightening device comprising two 80 parallel fixed rods in front of which the knit fabric passes; a pulling rod parallel to said fixed rods behind which rod the knit fabric passes; mechanism to take up the fabric when knit; and devices intermediate the main shaft and pulling rod and operated from the main shaft and adapted to move the pulling rod between the fixed rods periodically for the purpose of drawing tightly 85 the thread loops upon the needles as said loops are leaving the needles, substantially as shown and described.

10. In a knitting machine, the combination of knitting mechanism comprising a plurality of needles; a main shaft; means from said shaft to actuate said mechanism and needles; a thread-supply for said needles; take-up rolls to receive the fabric knit by said needles from the thread-supply; two fixed parallel rods; a reciprocating rod movable to and from said fixed rods; a pivotally mounted rocker arm; two bars pivotally mounted on said rocker arm and supporting said reciprocating rod; a cam; a cam-shoe on said cam; a rod from the cam-shoe pivotally mounted on the rocker arm; and means to rotate said take-up rolls, cam and rocker arm in unison, all operating substantially as shown and for the purpose specified.

11. In a knitting machine, the combination of knitting mechanism; a plurality of needles; means adapted to impart a vertical reciprocating movement to said needles; means to impart a horizontal reciprocating movement to said needles; a thread-supply 110 for said needles; a main roller rotatably mounted on supports and having said thread supply wound thereon; a friction roller rotatably mounted upon said supports and located between said main roller and said needles and having each thread wound once around said friction roller; means for retarding the revolution of the friction roller; and a main shaft adapted to operate said knitting mechanism and said needles.

12. In a knitting machine, the combination of knitting mechanism; a plurality of needles; means adapted to impart reciprocating knitting movements to said needles; a rotatably mounted main roller having a 120

- thread-supply wound thereon for said needles, respectively; a rotatably mounted friction roller adapted to receive threads from the main roller and deliver the same to the needles, respectively, as drawn by said needles, said threads being wound once around the friction roller, respectively; and elastic means for retarding the rotation of the friction roller in timed relation with the operation of the needles; and a main shaft adapted to operate said knitting mechanism and needles.
13. In a knitting machine, the combination of knitting mechanism; a plurality of needles; means adapted to impart reciprocating knitting movements to said needles; a rotatably mounted main roller; a supply of threads wound on said roller for said needles and drawn by said needles in their knitting movements; a rotatably mounted friction roller having a circumferential channel and adapted to conduct thread from the main roller to the needles, respectively, around which friction roller each thread is once wound; a friction strap passing over the friction roller in the channel thereof; needle-lifting devices adapted to give periodical, reciprocating, vertical movements to the needles; two springs connected to the two ends of the friction strap and fastened at their opposite ends to the needle-lifting devices; and a main shaft adapted to operate said needles and said knitting mechanism.
14. In a knitting machine, the combination with a plurality of needles situated in a row, of means to reciprocate said needles in the direction of their length, means to move said row of needles bodily in a direction at right angles to the length of the needles, a thread supply for the needles, tensioning means for the thread, and means to increase the tension on the thread as the needles are drawing fresh loops through the previously-formed loops and to release the tension thereof as the needles rise through the last-formed loops.
15. In a knitting machine, the combination of a main shaft; a needle-bar operated from the main shaft and adapted to a vertical reciprocating movement; needles supported by the needle-bar; a needle-lifting bar engaging said needles and adapted to a vertical reciprocating movement and operated from the main shaft; means operated from the main shaft and adapted to impart a horizontal reciprocation to said needle-bar and needle-lifting bar; means for supplying threads to said needles; a rotatable cam-shaft; a cam on the cam-shaft; a push-rod operated by said cam and capable thereby of a vertical reciprocating movement; a series of pivotally mounted thread-carriers arranged in shear-like pairs and adapted to conduct said threads to the needles; and a lazy-tongs device connected with said push-rod and adapted to alternately open and close said thread-carriers.
16. In a knitting machine, the combination of knitting mechanism; a plurality of needles; means adapted to impart horizontal reciprocating movements to said needles; needle lifting means adapted to impart periodical, vertical reciprocating movements to the needles; a rotatably mounted main roller adapted to have wound thereon a thread supply for said needles; a revolvably mounted tension roller intermediate the main roller and the needles around which roller each thread is wound one turn; a friction strap passing over the tension roller and connected to the needle lifting means and to the frame whereby said tension roller is alternately retarded and released when the machine is operated.
17. In a knitting machine the combination of knitting mechanism; a plurality of needles; means adapted to impart horizontal reciprocating movements to said needles; means adapted to impart periodical vertical reciprocating movements to the needles; a rotatably mounted main thread roller adapted to have wound thereon a thread supply for said needles; a rotatably mounted tension roller intermediate the main thread roller and the needles around which roller each thread from said thread supply is wound one turn during its passage to the needles; a friction strap having elastic ends, passing over the tension roller, one of said ends being connected to the vertical reciprocating means, and the other end being connected to a stationary part of the machine whereby said friction strap is alternately tightened or released when the machine is operated.
18. In a knitting machine, the combination with a plurality of needles arranged in a row, of means to reciprocate said needles in the direction of their length, means to reciprocate the row of needles bodily in a direction at right angles to the length of the needles, a thread supply for the needles, thread-tensioning means for the thread supply situated between said thread supply and needles, and means to cause said tensioning means to apply an increased tension to the thread as the needles are drawing fresh loops through the previously-formed loops and to release the tension as the needles rise through the last-formed loops.
19. In a knitting machine, the combination with a plurality of needles arranged in a row, of means to reciprocate said needles in the direction of their length, means to reciprocate the row of needles bodily in a direction at right angles to the length of the needles, a thread supply for the needles, thread-tensioning means for the thread sup-

- ply situated between said thread supply and needles, means to cause said tensioning means to apply an increased tension to the thread as the needles are drawing fresh loops through the previously-formed loops and to release the tension as the needles rise through the last-formed loops, and means to render said machine inoperative upon the breakage of a thread.
- 10 20. In a knitting machine a plurality of needles suitably mounted; means to impart a horizontal reciprocating movement to said needles; means to impart to said needles a periodical vertical reciprocating movement; a thread supply for said needles; tensioning means for said thread supply between said thread supply and needles adapted to alternately retard or release said threads on their passage to the needles upon the operation 75
- 15 of the vertically reciprocating means; take up mechanism; and means between said takeup mechanism and said needles adapted to draw tight the stitches formed by said needles upon their leaving the same; in combination with means to render said machine inoperative upon the breakage of a thread.
- 20 21. In a knitting machine a plurality of needles suitably mounted; means to impart a horizontal reciprocating movement to said needles; means to impart to said needles a periodical vertical reciprocating movement; a thread supply for said needles; tensioning means for said thread supply and means operated by the needle-reciprocating means to alternately retard and release the thread upon the operation of the machine.
- 25 22. In a knitting machine a plurality of needles suitably mounted; means to impart a horizontal reciprocating movement to said needles; means to impart to said needles a periodical vertical reciprocating movement; a thread supply for said needles; tensioning means for said thread supply, means operated by the needle-reciprocating means to alternately release and retard the thread during its passage to the needles upon the operation of the machine; and means to draw tight the stitches formed by said needles after the stitches are removed from 90
- 30 the needles.
- 35 23. In a knitting machine a plurality of needles suitably mounted; means to impart a horizontal reciprocating movement to said needles; means to impart to said needles a periodical vertical reciprocating movement; a thread supply for said needles; tensioning means for said thread supply whereby said thread supply is alternately tensioned and released during its passage to the needles; means to draw tight the stitches formed by said needles after the stitches are removed from the needles; in combination with means to render said machine inoperative upon the breakage of a thread.
- 40 24. In a knitting machine a plurality of needles suitably mounted; means to impart a horizontal reciprocating movement to said needles; means to impart to said needles a periodical vertical reciprocating movement; a thread supply for said needles; tensioning means for said thread supply; means acting through the knit fabric and operating to draw tight the stitches formed by said needles after the stitches have left the needles.
- 45 25. In a knitting machine, the combination with knitting mechanism including reciprocating needles, of a thread tension device acting on the thread as it passes to the needles and provided with means to apply increased tension to the thread as the needles are drawing fresh loops through the previously-formed loops.
- 50 26. In a knitting machine, the combination with knitting mechanism including a plurality of needles and means for operating them, of a thread supply for said needles, and tensioning means for said thread supply between the latter and the needles adapted to alternately retard or release said threads on their passage to the needles and in timed relation to the movement thereof.
- 55 27. In a knitting machine, the combination with knitting mechanism including a plurality of needles and means for operating them, of a thread tension device acting on the thread as it passes to the needles, and means to cause said tension device to apply a greater tension to the thread while the needles are drawing fresh loops through the previously-formed loops than during the return movement of the needles.
- 60 28. In a knitting machine, the combination with knitting mechanism including knitting needles and means to operate them, of a thread tension device acting on the thread passing to the needles and provided with means to apply an increased tension to the thread while the needles are drawing fresh loops through the previously-formed loops, a take-up for the knit fabric, and means between said take-up and said needles to draw tight the stitches formed by said needles after the latter leave the stitches.
- 65 29. In a knitting machine, the combination with knitting mechanism including knitting needles and means to operate them, of a thread tension device acting on the thread passage to the needles and provided with means to apply an increased tension to the thread while the needles are drawing fresh loops through the previously-formed loops, and means acting on the knit fabric to apply increased tension thereto during the return movement of the needles.
- 70 30. In a knitting machine, the combination with knitting mechanism including

knitting needles and means to operate them, of a thread supply for the needles, and means acting on the knit fabric and operating in timed relation to the movement of the 5 needle to apply increased tension to the fabric after the needles have drawn the last-formed loops through the previously-formed loops and while the needles are moving into

position to receive the thread again for fresh loops.

In testimony whereof I affix my signature in presence of two witnesses.

JOHN WATERFIELD.
